NESTABLE TRAY FOR LABORATORY INSTRUMENTS

Lydia E. Engel, 7844 Glencoe, Huntington Beach, Calif. 92647

Filed Nov. 21, 1966, Ser. No. 4,759

Term of patent 14 years

(Cl. D16—1)

FIG. 2

FIG. 3.

FIG. 1 is a top perspective view of a nestable tray for laboratory instruments, embodying my new design;

FIG. 2 is a top plan view thereof;

FIG. 3 is a bottom perspective view thereof;

FIG. 4 is a side elevation thereof; and

FIG. 5 is an end elevation thereof.

The broken lines are shown for illustrative purposes only.

I claim:

The design for a nestable tray for laboratory instruments, as shown and described.
